HAIR CURLER

Dorlane Archer, Los Angeles, Calif.

Application March 8, 1941, Serial No. 382,492

7 Claims. (Cl. 132—41)

This invention relates to a hair curling device and it is a general object of the invention to provide a simple, inexpensive, and very effective hair curler of the type wherein a strand of hair is wound or curled about an element which remains on the person's head for as long as required to give the strand a set or curl.

Another object of this invention is to provide a hair curling device of the character referred to that is characterized by its simplicity of construction and low manufacturing cost.

Another and important object of the invention is to provide a hair curling device of the character referred to that is easy and convenient to use and that remains in place until deliberately removed.

Another object of the invention is to provide a hair curler of the character mentioned that is small, compact, and inconspicuous.

A further object of this invention is to provide a hair curler of the character referred to that does not embody pins, sharp edges, or other hazardous parts liable to cut or break the hair, and that cannot be fouled or tangled in the hair.

The various objects and features of my invention will be fully understood from the following detailed description of a typical preferred form and application of the invention, throughout which description reference is made to the accompanying drawing, in which:

Fig. 1 is a fragmentary elevation view of the hair curler in the open or extended condition, showing the end portion of a hair strand initially engaged therein. Fig. 2 is a view similar to Fig. 1 with the strand curled or wound on the device. Fig. 3 is a view similar to Fig. 2 showing the device latched or retained on the curled strand. Fig. 4 is a side or edge view of the device in the condition illustrated in Fig. 3. Fig. 5 is a fragmentary longitudinal detailed sectional view taken substantially as indicated by line 5—5 on Fig. 1, and Fig. 6 is a perspective view of the device.

The improved hair curler of my invention may be said to comprise, generally, a forked spindle element 10 on which the strand S of hair is to be wound, and a carrier and keeper 11 supporting the element 10.

The element 10 forms a mandrel or spindle on which the hair strand is wrapped or wound. In accordance with the invention the element 10 is of special formation to grip and retain the end portion of the strand S and thus greatly facilitate the spooling or curling of the hair strand.

The element 10 comprises two tines, arms or fingers 12. The fingers 12 are elongate parts with straight longitudinal edges and rounded outer ends 13. The inner opposing surfaces of the fingers 12 are flat to better engage or grip the hair strand S. The outer surfaces of the fingers 12 are rounded or convex, the fingers being substantially semi-cylindrical in transverse cross section. With this formation the two fingers 12 form a generally cylindrical spool on which the hair strand may be wound to assume a substantially cylindrical curl form. In the preferred construction the element 10 is an integral or one-piece member, the two fingers 12 being integrally joined at their inner ends. The connecting portion 14 connecting or joining the fingers 12 forms a hub or bearing for pivotally mounting the fingers on the carrier and keeper 11. The bearing portion 14 is substantially cylindrical in transverse cross section and is tubular having a longitudinal opening 15 whose axis is transverse of the long axis of the element 10. The hair gripping and spooling element 10 is constructed so that its fingers 12 normally tend to diverge or flare slightly from the connecting portion 14 and the resiliency of the element restores the fingers 12 to this condition when freed after use. The element 10 may be formed of metal, pyroxylin, plastic, or other material having the desired qualities of flexibility and resiliency. It will be observed that the element 10 is a simple, inexpensive, readily formed part.

The carrier and keeper 11 serves as a support or mounting for the element 10 and as a keeper for retaining the curled strand S in the curled condition on the element 10. In the preferred construction the carrier and keeper 11 is an elongate strap-like part having straight longitudinal edges and generally flat surfaces. It is to be understood that the edges of both the element 10 and the keeper 11 may be smooth and rounded. As illustrated in the drawing, the carrier and keeper 11 is somewhat wider than the element 10 and is of substantially the same length as the element 10. The inner end part of the keeper 11 is formed to pivotally support the hair gripping and spooling element 10. Upturned ears 16 are provided on the opposite edges of the inner end of the carrier and keeper 11. The bearing portion 14 of the element 10 is received between the ears 16. A pivot pin 17 is carried in openings in the ears 16 and passes through the opening 15 to pivotally mount the element 10 on the carrier and keeper 11. The ends of the pin 17 are upset, riveted or headed

over to prevent displacement of the pin and to remove sharp edges and corners. The element 10 and the keeper 11 are connected by the pin 17 so that they may be swung between the extended positions illustrated in Figs. 1, 2 and 5 of the drawing and the active positions illustrated in Figs. 3 and 4.

The outer portion of the carrier and keeper 11 is formed to latch or retain the element 10 so that the strand S wrapped thereon is gripped or held between the element 10 and the keeper 11 and thus maintained in the wrapped or curled condition. An opening 18 is provided in the outer end part of the carrier and keeper 11 to receive the outer portions of the fingers 12. In practice the opening 18 may be square or rectangular and is proportioned to receive the fingers 12 with suitable clearance. When the strand S is wound or curled on the element 10 the element and the keeper 11 are swung or hinged together. This causes the strand S to be gripped between the element 10 and the keeper 11 and results in the flexing or bowing of both the element 10 and the keeper 11 and allows the outer end portion of the element 10 to enter or snap into the opening 18. The resiliency of the bowed element 10 and the keeper 11 maintains the outer surface of the uppermost finger 12 in tight engagement with the end wall of the opening 18 and this engagement retains the element 10 and the keeper 11 in the active positions. The rounded outer ends 13 of the fingers 12 are readily slipped or snapped into the opening 18.

The carrier and keeper 11 described above is formed of a selected material having the desired flexibility and resiliency. The carrier and keeper 11 may be formed of a suitable metal, pyroxylin, plastic, fibrous material, paper, or the like. The element 10 and the keeper 11 may be of any selected colors, finishes, etc., and may be plated or ornamented as desired.

It is believed that the utility and practicability of the hair curler of this invention will be apparent from the foregoing detailed description. In use the element 10 and the keeper 11 are preferably extended and the outer end portion of the hair strand S is inserted between the fingers 12, as illustrated in Fig. 1 of the drawing. It is preferred to space the strand S between the ends of the fingers 12 leaving free or unoccupied portions at the opposite ends of the fingers. The strand S is then wound on the element 10 as by rotating or turning the device while maintaining a suitable tension on the strand. With the hair strand S wound on the element 10 as shown in Fig. 2 of the drawing the carrier and keeper 11 is pivoted to the active position to engage against the wound strand S. As above described, this results in the flexing or bowing of both the element 10 and the keeper 11 and the parts may be manipulated to cause the fingers 12 to enter or snap into the openings 18. With the fingers 12 engaged in the opening the curled strand S is securely held or retained. When it is desired to remove the curler the carrier and keeper 11 is pivoted and flexed outwardly with respect to the element 10 to disengage the element 10 from the opening 18 and the fingers 12 are withdrawn from the curled strand S. As above described, the fingers 12 return to their spread or flared condition when released and the flaring fingers are easily disengaged from the curled strand.

Having described only a typical preferred form and application of my invention, I do not

wish to be limited or restricted to the specific details herein set forth, but wish to reserve to myself any variations or modifications that may appear to those skilled in the art, or fall within the scope of the following claims.

Having described my invention, I claim:

1. A hair curler of the character described comprising an elongate spindle element having a pair of fingers in face to face relation and flaring apart from their inner ends to receive the end portion of a hair strand whereby the strand may be wound on the element, a keeper pivotally connected with the inner end of the spindle element to be swung from an extended position to a position where it extends along the side of the element in face to face relation to one of its fingers to engage and retain the strand, and means for releasably latching the outer ends of the element and keeper together to retain the keeper in the last named position.

10 2. A hair curler of the character described comprising an elongate spindle element having a pair of fingers flaring apart from their inner ends to receive the end portion of a hair strand whereby the strand may be wound on the element, a keeper pivotally connected with the inner end of the spindle element to be swung from an extended position to a position where it extends along the side of the element in face to 15 25 30 35 40 45 50 55 60 65 70 75 80 85 90 95 100 face relation to one of its fingers to engage and retain the strand, the element and keeper being formed of flexible material so that they are bowed due to the presence of the curled strand when the keeper is brought to said second position, and means for latching the keeper in said second position comprising walls on the keeper defining an opening for receiving the outer end part of the element.

3. A hair curler of the character described comprising a spindle element on which a strand of hair is to be wound, the element including a pair of flexible, slightly diverging fingers between which the end of the strand may be engaged and an inner end portion connecting the fingers, an elongate flexible keeper, means connecting the inner end of the keeper and said inner end portion of the element so that the keeper may be swung from an extended position to an active position where it is in face to face relation to one of said fingers to clamp against the wound strand, the element and keeper being bowed outwardly between their ends due to the engagement of the keeper with the wound strand so that the outer ends of the keeper and element tend to cross, and means for latching the keeper in the active position.

4. A hair curler of the character described comprising a spindle element on which a strand of hair is to be wound, the element including a pair of flexible, slightly diverging fingers between which the end of the strand may be engaged and an inner end portion connecting the fingers, an elongate flexible keeper, means connecting the inner end of the keeper and said inner end portion of the element so that the keeper may be swung from an extended position to an active position where it clamps against the wound strand, the element and keeper being bowed outwardly between their ends due to the engagement of the keeper with the wound strand so that the outer ends of the keeper and element tend to cross, and means for latching the keeper in the active position, said means comprising walls on the keeper defining an opening for receiving the outer end portion of the element

to retain the same where it is in the crossed relation to the keeper.

5. A hair curler comprising two flexible elongate members, one a spindle on which a strand of hair is to be wound, the other a keeper, means for pivotally connecting the inner ends of the members whereby the keeper may be swung against the wound strand to maintain the same in the wound state, the members bowing apart between their ends so that their outer portions tend to cross when the keeper is brought to the active position, and means for latching the keeper in the active position comprising walls on the outer portion of one member defining an opening for receiving the outer portion of the other member when said portions cross.

6. A hair curler comprising two flexible elongate members, one a spindle on which a strand of hair is to be wound, the other a keeper, said members each being one-piece elements, means for pivotally connecting the inner ends of the members whereby the keeper may be swung against the wound strand to maintain the same in the wound state on the spindle, the members bowing apart between their ends so that their outer portions tend to cross when the keeper is brought to the active position, and means for latching

the keeper in the active position comprising walls on the outer portion of one member defining an opening for receiving the outer portion of the other member when said portions cross.

5 7. A hair curler of the character described comprising a spindle element on which a strand of hair is to be wound, the element including a pair of flexible, slightly diverging fingers between which the end of the strand may be engaged and an inner end portion connecting the fingers, said fingers and portion being integral and said portion being of tubular form, a flexible keeper having a pair of spaced ears integral therewith, a pin extending between the ears and passing through said tubular portion to pivotally connect the spindle element and keeper whereby the keeper may be brought in face to face relation with the spindle element so that it engages against the strand wound on the spindle element to keep it in the wound state, the outer end parts of the spindle element and keeper tending to cross when the keeper is forced against the wound strand, and walls on the keeper defining an opening which receives the outer end portion of the spindle element to latch the keeper in the active position.

DORIANE ARCHER.
